US0D1043423S

(12) **United States Design Patent** (10) **Patent No.:** **US D1,043,423 S**
(45) **Date of Patent:** **** Sep. 24, 2024**

(54) **WATCH CLASP**

(71) Applicant: **TUDOR WATCH U.S.A., LLC**, New York, NY (US)

(72) Inventor: **Ander Ugarte**, Geneva (CH)

(73) Assignee: **TUDOR WATCH U.S.A., LLC**, New York, NY (US)

(**) Term: **15 Years**

(21) Appl. No.: **29/823,706**

(22) Filed: **Jan. 19, 2022**

(30) **Foreign Application Priority Data**

Jul. 20, 2021 (CH) 146218
